UNITED STATES PATENT OFFICE.

MOSES H. DUNN, OF LOS ANGELES, CALIFORNIA.

HYDROCARBON-BURNER.

1,102,329.

Specification of Letters Patent.

Patented July 7, 1914.

Application filed October 23, 1913. Serial No. 796,826.

To all whom it may concern:

Be it known that I, MOSES H. DUNN, a citizen of the United States, residing at Los Angeles, county of Los Angeles, and State 5 of California, have invented certain new and useful Improvements in Hydrocarbon-Burners, of which the following is a specification.

This invention relates to hydrocarbon 10 burners.

My invention has for its objects the provision of a simple, durable, and highly efficient burner adapted to use crude oil in connection with steam or air under pressure and 15 which, due to its improved construction and the relationship of the nozzles of its steam or air and oil pipes, sprays the oil to a relatively great distance, affording a superior delivery and combustion without the accumulation 20 of any hydrocarbon deposit at the nozzle or mouth and thereby overcomes a defect incident to burners of this general type.

In my burner the superior results obtained are due to the nozzle construction, particularly that of the inner or oil tube; and its relation to the outer or air or steam tube and to the approximate distance between the end of the outer nozzle and the 30 end of the nozzle of the inner or oil tube. However, I prefer to provide means whereby a certain adjustment of the inner tube may be obtained. I have found, in practice, that the improved construction at the 35 mouth or nozzle of the inner tube, by its cooperation with the outer tube, while choking the air under pressure or steam, permits the liberation of the steam or air in such manner that it commingles with the oil and 40 forms the latter into a spray which is projected with considerable force for a relatively great distance, and the burner is thereby adapted for use in connection with steam boilers and insures the flame reaching 45 well up around the sides of the boiler and evenly through the tubes or over the surface and walls of the furnace, as the case may be. At the same time, the nozzle does not clog with hydrocarbon deposit.

An embodiment of the invention adapted 50 to carry out the foregoing objects and results is set forth fully hereinafter, but it is to be understood that I do not limit myself to the exact sizes and proportions of the 55 parts nor to the details of construction except where specified in the claims.

In the accompanying drawings: Figure 1 is a side elevation; Fig. 2, a longitudinal section; Fig. 3, a cross section on line 3—3, Fig. 2; and Fig. 4, a detail perspective of 60 the nozzle at the end of the inner tube.

The air or steam tube 1 is provided with a nozzle or mouth 2 of elongated form which is longer than the internal diameter of the said tube. The tube 1 is screwed at 3 into a union 4 which is adapted to receive air or steam at 5 from any suitable pipe. The inner or oil tube 6 has screw threads 7 engaged with the nut 8, the latter being screwed into the union at 9. By this means 65 the oil tube is subject to adjustment longitudinally, to a limited extent, in relation to the tube 1. The tube 6 is of somewhat smaller diameter externally than the internal diameter of the tube 1, whereby the air 70 or steam may pass along the tubes and between them on its way to the nozzle or mouth 2. The end of the tube 6 is flared at 75 10 in general conical or beveled form up to the narrow flattened and circular part 11 80 which fits the interior of the tube 1 at a distance inwardly from the nozzle 2. Usually in a small size of the burner where the internal diameter of the tube 1 is, say, three-quarters of an inch and the internal diameter 85 of the tube 6 is one-half of an inch, length of tube 1 would be about twelve to fifteen inches and that of tube 6 approximately nine to twelve inches. In larger sizes of the 90 burner, the distance between the nozzle 2 and nozzle of tube 6 may be as great as nine inches, more or less as, for instance, where the internal diameter of the tube 1 is one and one-quarter inches and the internal diameter of the tube 6 is one-half inch, the 95 length of the tube 1 may be thirty inches and that of tube 6 about twenty-one to twenty-two inches. I have found, by experiment, that these distances have a relationship to the efficiency of the burner, but 100 in stating them, I do not limit myself, except where specified in the claims. Between the above limits, the longer the outer tube 1, the farther the nozzle end of inner tube 6 should be from the nozzle 2 of outer tube, in 105 order that the oil and steam may become thoroughly united so that on leaving the burner all will be consumed and transformed into heat. Originating in the outer surface of the tube 6, grooves 12 extend longitudinally of the tube through the beveled or conical part 10 and the part 11, as at 13,

widening until they reach their greatest width at the extreme end of the tube 6, said end being concaved or beveled at 14, thereby providing the sharp circular edge 15. This 5 construction chokes the air or steam where the surface 11 fits the interior of the tube and the air or steam escapes, at considerable pressure, in the form of jets issuing through the grooves 12 and forces the oil issuing 10 from pipe 6, out through the nozzle 2 in the form of a spray which is widely spread and projected with considerable velocity.

Having thus described my invention, what I claim as new and desire to secure by Letters Patent, is:—

1. In an oil burner, the combination with an outer tube having a nozzle or mouth, of an inner tube of smaller external diameter than the interior of the outer tube and provided with a coned or flared end whose largest part or base substantially fits the interior of the outer tube, said flared end being provided with external grooves which are widest at their discharge end and taper or decrease in size inwardly until they sub-

stantially merge into the outer surface of the inner tube, said coned or flared end being located inwardly in relation to the nozzle of the outer tube.

2. In an oil burner, the combination with an outer tube having a nozzle or mouth, of an inner tube of smaller external diameter than the interior of the outer tube and provided with a coned or flared end having a cylindrical part at its largest diameter substantially fitting the interior of the outer tube, said flared end being provided with external grooves which are widest at their discharge end and taper or decrease in size until they substantially merge into the outer surface of the inner tube, the end of the inner tube having an internal bevel which provides a relatively sharp circular end thereon.

In testimony whereof, I hereunto affix my signature in presence of two witnesses.

MOSES H. DUNN.
